UNITED STATES PATENT OFFICE.

HERMANUS THOMASSEN, OF HEELSUM, NEAR ARNHEM, NETHERLANDS.

NUT-LOCKING DEVICE.

1,281,709.

Specification of Letters Patent. Patented Oct. 15, 1918.

Application filed April 16, 1917. Serial No. 162,462.

To all whom it may concern:

Be it known that I, HERMANUS THOMASSEN, residing at Heelsum, near Arnhem, The Netherlands, have invented certain new and useful Improvements in Nut-Locking Devices, of which the following is a specification.

This invention relates to certain improvements in nut locking devices.

10 The object of the invention is to provide a nut locking device exceedingly simple in construction, besides being perfectly sure and effective in operation.

15 The invention consists in certain novel features in construction more fully described hereinafter and particularly pointed out in the claims.

20 Referring to the accompanying drawing: Figure 1, is a sectional view of a screw bolt with nut and nut lock constructed in accordance with the principles of the present invention. Fig. 2, shows a cross-section on line A—A in Fig. 1. Figs. 3, 4 and 5 are sectional views of two somewhat different 25 embodiments of the invention. Fig. 6, is a cross-section on line B—B in Fig. 5.

30 In the device illustrated in Figs. 1 and 2, the reference numeral 1 indicates a bolt, and 2 a nut. From its right hand face the nut 2 has been eccentrically turned out to a certain depth so that an eccentric groove and a collar or eccentric ring 3 is formed, the depth of the eccentric bore being such that the height of the threaded portion of 35 the nut is normal for the size of bolt 1.

35 The nut lock consists of a sleeve 4 being provided with a smooth bore with a diameter equal to or only slightly exceeding the external diameter of the bolt 1. The left 40 hand face of said sleeve is provided with an eccentric ring or collar 5 whose eccentricity may be the same as that of the ring 3, and whose external diameter is slightly smaller than the internal diameter of the 45 collar 3; this difference however should be less than four times the eccentricity of the collars. The right hand portion of the sleeve 4 has preferably the usual hexagonal form so that the lock may be turned by 50 means of a spanner fitting the nut.

55 After the nut 2 has been screwed on the bolt 1 and spanned, the locking sleeve 4 is passed on the bolt so that the axes of the eccentric ring 3 are substantially parallel with those of the ring 5, after which the latter is introduced lengthwise into the ring

3. The locking sleeve 4 is now turned to the right, thereby getting jammed against the inner wall of the collar 3, so that the nut as well as the locking sleeve are firmly 60 pressed against the bolt. This jamming action is still increased if the rut is turned to the left or when it tends to work loose.

If it is desired to unscrew the nut the locking sleeve needs simply be turned with 65 a spanner a certain angular distance in the reverse direction, *i. e.*, to the left, when it will no longer be jammed against the inner wall of the ring 3, and the sleeve 4 can be 70 slid off the bolt.

In the example given the coating surfaces of the rings 3 and 5 are cylindrical; if desired however these surfaces may be slightly conical, or otherwise formed, whereby the locking effect may still be increased, although it has been found in practice that cylindrical surfaces insure sufficient grip for positively preventing the nut from working loose. Reference is had to 75 Fig. 3, showing an embodiment of the invention wherein the said surfaces are slightly conical. It will be readily understood that after the eccentric ring 5 has duly been introduced into the eccentric bore of the nut 2, and then turned a certain angular distance it is impossible for the sleeve 4 to be 80 lengthwise withdrawn from the nut, also in case the coating surfaces of the rings 3 and 5 are not yet in gripping engagement.

85 Fig. 4 shows another device differing 90 from that illustrated in Figs. 1 and 2 only in that the eccentric ring or collar 7 of the locking sleeve 4 fits around instead of within the eccentric ring 6 of the nut 2. It is clear 95 that the ring 6 needs not necessarily be threaded, and that it is neither essential that it exactly fits the bolt 1.

100 Referring to Figs. 5 and 6, the nut 2 is provided with an eccentric groove 8 and the locking sleeve 4 with an eccentric ring 9 fitting with some clearance within the groove 8 if the nut 2 and the sleeve 4 have the correct position the one with respect to the other. The nut in this case may be considered as being provided with two eccentric rings forming the walls of the groove 8.

105 It will be understood that for an effective operation of my improved nut locking device the eccentricity of the rings or collars provided on the nut and on the locking sleeve should be comparatively very small.

110 It is evident that various changes might

be made in the construction described without departing from the spirit and scope of my invention. Hence I do not wish to limit myself to the construction herein set forth, 5 but consider myself entitled to all such changes as fall within the spirit and scope of my invention.

Having thus described my invention, I claim as new and desire to secure by Letters 10 Patent:—

1. A device of the character described including a bolt, a nut in threaded engagement with the bolt and having an eccentric groove in one face thereof, and a locking sleeve 15 having a smooth bore equal to or slightly exceeding the external diameter of the bolt and provided on one of its faces with an eccentric ring adapted to coact with said eccentric groove in the nut to be interlocked therewith and also lock the said nut on the bolt.

2. A device of the character described in-

cluding a bolt, a nut in threaded engagement with the bolt and having an eccentric groove in one face thereof, and a locking sleeve having a smooth bore equal to or slightly exceeding the external diameter of the bolt and provided on one of its faces with an eccentric ring fitting with some clearance within said eccentric groove in said nut to be interlocked therewith and also lock the said nut on the bolt. 25

3. A nut locking device comprising in combination, the bolt and co-acting sleeve and nut members, one of which has a threaded engagement with the bolt and the other of which has a bore adapted to slidably work over the threads, the said co-acting members also respectively having interengaging eccentric ring and groove elements. 30

In testimony whereof I have affixed my signature.

HERMANUS THOMASSEN.
